UNITED STATES PATENT OFFICE.

OTTO N. HICKS, OF FILLMORE, INDIANA.

VENDING AND DISPLAY CASE.

Application filed September 12, 1924. Serial No. 737,404.

This invention relates to a vending device, the general object of the invention being to provide means for discharging articles from a display case forming part of the device by the manipulation of a certain lever so that a clerk can deliver to a customer the desired article from the case without handling the same and without touching the other articles in the case.

Another object of the invention is to provide a normally closed gate for the display case with means for opening the same when a lever is depressed.

A further object of the invention is to provide an alarm which will be sounded when a lever is depressed.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a front view of the device.

Figure 2 is a side view thereof.

Figure 3 is a plan view with parts broken away.

Figure 4 is a bottom plan view of portion of the device.

Figure 5 is a transverse sectional view with the parts in closed position.

Figure 6 is a similar view with the parts in a position for discharging an article.

In these views, 1 indicates a housing which is adapted to be placed on a counter or other support and to which is attached a display case 2, portions of this display case being formed of transparent material, as shown at 3. Rods 4 are arranged in pairs in said case and form partitions for dividing the same into a plurality of compartments, each compartment being designed to receive the articles to be vended, such articles being shown in dotted lines at A. The articles may be introduced into the case in any suitable manner. The rear lower part of the case is in communication with the interior of the housing 1 so that any one of a plurality of plungers 5 may have their forward ends enter the lower part of the case to shove an article therefrom through the

opening 6 which is normally closed by a gate 7. The plungers 5 are guided in their reciprocatory movements by the rods 8 which are supported by the cross pieces 9 in the housing. A spring 10 connects a part of each plunger with one of the cross pieces 9 and tends to hold the same in its retracted position. A plurality of hand levers 11 are pivotally supported in the housing by means of the rod 12, these levers being of bell crank shape and extending through slots 14 formed in the housing. The outer end of each lever is provided with a finger engaging part 15 and the inner end of each lever is connected with a plunger by the links 16 so that when a lever is depressed the plunger will be projected so that its forward end will enter the casing 2 and engage the lowermost article therein and force it through the opening 6. A frame 17 is pivoted in the housing 1 and this frame is adapted to be rocked by having a part thereof engaged by a beveled edge 18 of a plunger when the plunger is projected so that the gate 7 will be raised to uncover the opening 6 as said gate is connected with the frame 17 by means of the rods 19 which are hingedly connected with the frame 17, as shown at 20. As the frame is actuated by a plunger a part thereof will strike the hammer 21 of a bell 22 so as to ring the bell and thus give warning that an article is being expelled from the case.

From the foregoing it will be seen that after a customer has indicated the article he desires to purchase, the articles being in full view through the transparent part of the case, the clerk will manipulate the proper lever so that the plunger to which the lever is connected will be projected to rock the frame 17 to open the gate 7 and then the forward part of the plunger will engage the lowermost article of the stack of articles which the customer wishes and expel the same from the case. Thus the articles are kept in a dust proof case and they are not handled by the clerk or customer. As soon as the lever is released the spring 10 will return the parts to normal and closed position.

It is thought from the foregoing description that the advantages and novel features of my invention will be readily apparent.

I desire it to be understood that I may make changes in the construction and in the

combination and arrangement of the several parts, provided that such changes fall within the scope of the appended claim.

What I claim is:—

- 5 A vending machine comprising a housing, a display case having transparent walls supported by the housing, said display case having an outlet opening in its lower end, a gate for closing the opening, a frame pivoted in the housing, rods connecting the frame with the gate, a plurality of guide rods horizontally arranged in the housing, a plunger slidably supported by each pair of

rods, each plunger having a part for engaging the frame to tilt the same when the plunger is projected, springs for holding the plungers in retracted position and hand levers pivotally supporting the housing and each connected with the plunger for projecting the plunger when the lever is depressed, each plunger having a part for entering the display case when the plunger is projected to force an article through the outlet opening therein.

In testimony whereof I affix my signature.
OTTO N. HICKS.
